Des. 202,518
Patented Oct. 12, 1965

202,518

MARINE COMPASS

Kaare Laerum, Drammensveien 59c, Oslo, Norway

Filed Dec. 4, 1963, Ser. No. 77,670

Claims priority, application Norway Sept. 24, 1963

Term of patent 14 years

(Cl. D52—6)

Fig. 2

Fig. 1

FIG. 1 is a plan view of the marine compass showing my new design; and

FIG. 2 is an elevational view of the compass showing my new design.

The essential features of the design reside in the portions shown in full lines.

I claim:

The ornamental design for a marine compass, as shown and described.
